UNITED STATES PATENT OFFICE.

HUGH J. McMAHAN, OF MONESSEN, PENNSYLVANIA, ASSIGNOR TO
WESTINGHOUSE ELECTRIC & MANUFACTURING COMPANY, A
CORPORATION OF PENNSYLVANIA.

CONTROLLER FOR SYNCHRONIZING SWITCHES.

No. 819,787.

Specification of Letters Patent.

Patented May 8, 1906.

Application filed April 10, 1905. Serial No. 254,792.

To all whom it may concern:

Be it known that I, HUGH J. McMAHAN, a citizen of the United States, and a resident of Monessen, in the county of Westmoreland and State of Pennsylvania, have invented a new and useful Improvement in Controllers for Synchronizing Switches, of which the following is a specification.

My invention relates to electrical apparatus, and particularly to means for controlling the operation of switches that are utilized for coupling electrical machines in parallel when they attain synchronous operation.

The object of my invention is to provide a simple, compact, and reliable means for so governing the operation of a coupling-switch that it shall connect a corresponding electrical machine in parallel with one or more other machines substantially at the instant when synchronous operation is reached.

In order to effect the desired result, I provide means for automatically timing the operation of the switch-governing means in accordance with the rate at which the machines approach synchronism.

In the accompanying drawings, Figure 1 is a view, partially in front elevation and partially in section, of the principal controlling features of my invention, the cover being removed. Fig. 2 is a plan view of the apparatus shown in Fig. 1, the casing being shown in section. Fig. 3 is a diagram of apparatus and circuits, illustrating the electrical connections and mode of operation of my invention; and Fig. 4 is a diagram similar to that shown in Fig. 3, but illustrating a modification.

The controller 1, which constitutes the principal element of my invention, comprises a number of co-operating elements which may be variously modified as to form and number and relation of parts and which may be mounted in a variety of ways; but, as here shown, the operating parts are mounted upon a back plate or base 2 and are inclosed and protected by a cover 3, which may be suitably fastened to the base 2. Projecting forwardly from the base 2 are a plurality of posts 4, to the outer ends of which is fastened a frame-plate 5, by means of screws 6. The frame-plate 5 is also provided with a plurality of posts 7, to the outer ends of which is fastened a plate or bar 8 by means of screws 9. The parts thus far described con-

stitute the frame which supports the movable parts of the instrument.

Journaled in suitable bearings, one of which is attached to the base 2 and the other to the frame-plate 5, is a shaft 10, upon which is rigidly mounted an arm or bar 11, which projects therefrom in both directions and which is provided with a hub or collar 12, that is adjustably clamped to the shaft 10 by means of set-screws or otherwise. The outer ends of the arm or bar 11 are respectively connected to the cores 13 and 14 of two solenoids 15 and 16, by means of coil-springs 17 and 18, so that as either core is drawn downward by the action of its solenoid the corresponding end of the arm or bar 11 will be lowered to correspondingly rock the shaft 10 in its bearings. The end of the bar 11 that is connected to the solenoid-core 14 is provided with an angular bracket-arm 19, the free end of which is pivotally connected to the upper end of a dash-pot cylinder 20 and which is also provided with a contact-brush 21, that projects inwardly substantially parallel to the base 2 toward the rock-shaft 10. The end of the bar 11 that is connected to the solenoid-core 13 is provided with a suitable weight 22 to counterbalance the dash-pot cylinder 20 and the other parts which are supported by the corresponding end of the bar 11.

The rod 23 of the dash-pot piston 24 is pivotally connected to one end of a lever 25, that is supported intermediate its ends on a short shaft or pivot 26, that has its bearings in the plates 5 and 8. The end of the lever 25 to which the piston-rod 23 is connected is also connected to a post 27, that projects from the base 2, by means of a coil-spring 28, a screw 29 being provided for adjusting the amount of pull exerted by the spring. The other end of the lever 25 is connected, by means of a link 30, to the outer end of an arm 31, which is loosely mounted upon a short shaft 32, the respective ends of which are journaled in the frame-plate 5 and the plate 8.

The portion of the arm 31 adjacent to the shaft 32 is provided with a fork 33. Rigidly mounted upon the shaft 32 between the plates 5 and 8 is a segmental block 34, preferably formed of insulating material and provided with a pin 35, that is so located between the prongs of the fork 33 as to be engaged by the

one or the other of them, according to the direction and relation of movement of the parts. The pin 35 is connected to a hub 36 of the arm 31 by means of a spiral spring 37, 5 which tends to move the segmental block 34 from left to right, and consequently to hold the pin 35 in engagement with the right-hand prong of the fork 33. The periphery of the segmental block 34 is provided with a conducting plate or strip 38, the outer surface of which is substantially flush with the peripheral surface of the block at one end, and at the other end the block is cut away to provide an offset. At the offset end of the block 10 34 a small insulating-block 39, having a slightly-inclined surface at its outer end, is set into a corresponding recess, so as to fit against the end of the plate 38 and provide a shoulder 39^a. 15

20 The brush-contact member 21, to which reference has already been made, makes engagement at its free end with the periphery of the segmental block 34, and a similar brush-contact member 40 is mounted in an arm 25 41, which in turn is adjustably supported by means of a slot-and-screw connection 42 with the frame-plate 5, so that it may be adjusted to vary the position of the free end of the brush 40 with reference to the contact strip or plate 38, with which the segmental block 34 is provided.

Referring now to Fig. 3 in connection with the preceding figures, two alternating-current machines 43 and 44, which may be assumed 35 as indicative of any number of generators, rotary converters, or synchronous motors which it may be desired to connect in parallel to either supply or utilize alternating-current energy, are respectively provided with double-pole switches 45 and 46, by means of which the machines may be connected to bus-bars 47 and 48. It will be understood that the bus-bars 47 and 48 may be connected, by means of suitable conductors, to translating devices in the usual manner and that it 40 is therefore unnecessary to illustrate such translating devices and circuit connections. I have shown each of the switches 45 and 46 as provided with means for automatically closing the same, such means being intended merely as indicative of any suitably-operated devices for this purpose. As here shown, the movable contact members of the switch 45 are connected together by a bar 45^a, 45 and the corresponding members of the switch 46 are similarly connected together by a bar 46^a. Each pair of movable members is connected, by means of a cord or band 49, to a weight 50, the cord or band being provided 50 with a catch or stop device 51 and being guided and supported by a suitable roller 52. The switches are normally held in open position by reason of the engagement with the catch 51 of a projection 53 from the core 54 55 of a solenoid 55, this projection being with-

drawn to permit the weight 50 to close the switch when the solenoid is energized to raise its core. The solenoids 55 are connected in parallel to a normally open circuit 56 57, that is supplied with energy from a suitable source, such as a battery 58. The brushes 21 and 40 of the controller constitute the terminals of the battery-circuit, and that circuit is therefore closed only when both brushes are in contact with the strip or plate 38 of the segmental block 34. This condition is aimed when and only when the machines 43 and 44 attain synchronous operation, and this condition may be brought about by any one of various arrangements and connections of circuits. 70

For the purpose of illustration I have shown the solenoids 15 and 16 as having their upper terminals connected, respectively, to the outer terminals of the secondary winding 59 of a transformer 60, the primary winding 85 of which is connected to the bus-bars 47 and 48, and as having their lower terminals connected together and to one terminal of the secondary winding 62 of each of two transformers 63, the primary windings 64 of which are connected across the terminals of the respective machines 43 and 44. The other terminals of the secondary windings 62 of the transformers 63 are connected to the middle point of the secondary winding 59 of the 95 transformer 60.

For convenience of description I have shown the switch 45 as closed, so that the machine 43 is connected to the bus-bars 47 and 48, and it will be assumed that it is operating at normal speed and that the other parts of the apparatus are in the positions indicated in the drawings. 100

If the machine 44 is to be connected to the bus-bars 47 and 48 to operate in parallel with the machine 43, it will be started with the switch 46 open, and so long as its periodicity is different from that of the machine 43 the current induced in the secondary winding 62 of the transformer 63, corresponding to the machine 44, will traverse the two halves of the secondary winding 59 of the transformer 60 in opposite directions and will also traverse both of the solenoids 15 and 16. Since the current is not in step with that induced in the secondary 59 by current derived from the generator 43, there will be substantial uniformity in the pull exerted by the two solenoids until the frequency of alternations supplied by the machine 44 becomes approximately the same as that supplied by the machine 43. When this condition is reached, the current in the half of the transformer secondary 59 that is connected to the solenoid 16 will oppose that induced in the said half by the primary winding, and the current supplied to the other half will be added to that induced therein, and consequently the solenoid 15 will be so energized as to exert a pull in excess of that exerted by the solenoid 115 120 125 130

16 and will thus serve to so rock the bar 11 as to move the brush 21 into contact with the strip or plate 38, and thus complete the circuit of the battery 58 and the solenoid 55. When this circuit is completed, the solenoid-core 54 will be lifted, thus releasing the weight 50, which will immediately close the switch 46, and thus connect the machine 44 to the bus-bars.

In case the approach to synchronism is slow and gradual the leakage of air into the dash-pot cylinder 20 will be such as to permit the cylinder to move independently of the piston 24, and consequently the brush 21 will be moved into contact with the strip 38 without any appreciable movement of the segmental block 34. If, however, the approach to synchronism is rapid, the pull upon the core 13 of the solenoid 15 will be correspondingly strong and the bar 11 will be rocked with sufficient rapidity to preclude the entrance of an appreciable amount of air into the dash-pot cylinder. The piston will therefore be moved with the cylinder and against the action of the spring 28, and the lever 25, the link 30, and the arm 31—the latter acting through one prong of its fork upon the pin 35—will serve to turn the segmental block 34 from right to left at the same time that the brush 21 is being moved in the opposite direction. This operation closes the battery-circuit more quickly than would be the case if the brush 21 only were moved, the result being that the main switch will be released at such an early period as compared with what would be the case if this provision for the closing of the battery-circuit were not provided that the main switch will be closed at the instant when synchronism occurs, whereas except for this provision the closing of the switch would be delayed and would not take place until after the occurrence of synchronism, and possibly in some cases not until the machines had reached such condition of non-synchronous operation that they could not be safely connected in parallel.

In case there is occasional phase coincidence of the currents from the two machines when they are operating under such conditions that they generate currents of widely different frequencies the occasional coincidence of phase will so energize the solenoid 15 as to cause it to exert such a sudden violent pull upon its core as to rock the block-segment 34 from right to left a distance greater than that through which it ordinarily moves, thus permitting the contact end of the brush 40 to drop behind the shoulder 39^a, thereby interrupting or preventing the closing of the auxiliary battery-circuit. This engagement of the contact end of the brush 40 with the shoulder 39^a serves to lock the segmental block in that position until the descent of the dash-pot plunger moves the fork 33 through the distance represented by the

difference between the diameter of the pin 35 and the space between the prongs of the fork. Further movement of the fork will force the shoulder 39^a from its locking position, and the spring 37 will quickly move the block 34 a ⁷⁰ sufficient distance to break the contact between the strip 38 and the finger 21.

Referring now to Fig. 4, the several devices and circuits there shown are the same as those illustrated in Fig. 3 and already described, except as regards one feature of the controller 1 and the connections between the same and the secondary winding 59 of the transformer 60. The parts to which no specific reference is made are given the same reference characters as in the preceding figures, and the description already given may therefore be read in connection with what is here shown. Instead of employing two solenoids 15 and 16, which normally counterbalance ⁸⁰ each other, I have here substituted a coil-spring 65 for the solenoid 16 of the structure before described. This spring is of such strength and is so adjusted as to counterbalance the pull exerted by the solenoid 15, except when the machines approach synchronism, in which case the current supplied directly to the secondary winding 59 supplements that induced therein by the primary winding, which is connected to the bus-bars, ⁹⁵ and then the pull of the solenoid 15 overcomes that of the spring 65 and the apparatus operates in the manner above described to release the main switch in order that it may be automatically closed to connect the ¹⁰⁰ corresponding machine in parallel circuit with the machine or machines already in operation.

The structural details and the combinations and arrangements of circuits and connections which I have shown and described may be varied in many particulars without departing from my invention, and I therefore desire to include within the scope of my claims all such variations and modifications ¹⁰⁵ as do not materially change the mode of operation or result.

I claim as my invention—

1. In a synchronizer for alternating-current dynamo-electric machines, a switch for coupling the machines, means for automatically closing the switch when the machines come into synchronism, a normally open governing-circuit having relatively movable contact-terminals, and an electromagnetically-actuated means for operating said contact-terminals, said means comprising a time-element-controlling device which prevents closure of the governing-circuit when the electromotive forces occasionally coincide in phase but are of materially different frequency, and which adjusts the time of such closure in accordance with the rate at which the machines are approaching synchronism. ¹²⁵

2. In a synchronizer for alternating-cur- ¹³⁰

- rent dynamo-electric machines, a switch for coupling the machines, a normally open switch-governing circuit, means actuated by the main circuits when the machines are synchronized to close the said switch-governing circuit, said means comprising time-element-controlling devices which serve to prevent closure of said switch-governing circuit when coincidence in phase occurs at intervals and the electromotive-force frequencies are materially unlike, and which also serve to insure closure of the switch-governing circuit at a time that corresponds to the rate at which the machines approach synchronism.
- 15 3. In a synchronizer for alternating-current dynamo-electric machines, a switch for coupling the machines, a normally open switch-governing circuit, an electromagnet that is energized by the main circuits when synchronism occurs, relatively movable contact members that are actuated by said magnet, when energized, to close said switch-governing circuit, and a time element for automatically varying the movement of said contact members in accordance with the frequency and phase relations of said machines.
- 20 4. In a synchronizer for alternating-current machines, a switch for coupling the machines, means for controlling the switch, and means for actuating the switch-controlling means earlier when the dynamos approach synchronism faster than a predetermined rate.
- 25 5. In a synchronizer for alternating-current machines, a switch for coupling the machines, means for governing the switch, a second switch for controlling the closing of the first switch, and means whereby the second switch will be closed earlier when the dynamos are approaching synchronism faster than a predetermined rate.
- 30 6. In a synchronizer for alternating-current machines, a switch for coupling the machines, means for closing the switch, a normally open circuit having means for energizing the switch-closing means when the machines approach synchronism, and means for closing the normally open circuit which embodies a variable time element device to prevent such closure when the electromotive forces of the machines have occasional phase coincidence but differ materially in frequency, and to effect such closure at such time as corresponds to the rate at which the machines approach synchronism.
- 35 7. In a synchronizer for alternating-current dynamo-electric machines, a switch for coupling the machines, means for governing the switch, and means for automatically timing the operation of the switch-governing means in accordance with the rate of approach of the machines to synchronism.
- 40 8. In a synchronizer for alternating-current dynamo-electric machines, a switch for coupling the machines, means for governing

the switch, a second switch for controlling the closing of the first switch, and means for automatically timing the operation of the second switch in accordance with the rate at which the machines are approaching synchronism.

45 9. In a synchronizer for alternating-current dynamo-electric machines, a switch for coupling the machines, means for governing the operation of the switch, comprising a normally open circuit, relatively movable circuit-closing members, operating-magnets, and dash-pot mechanism that regulates the movement of the circuit-closing members in accordance with the rate at which the machines approach synchronism.

50 10. Means for connecting a dynamo-electric machine in parallel circuit with one or more other similar machines at the instant when synchronism occurs, comprising an automatic switch and a governing device therefor having a stationary contact member and two movable contact members, one or more actuating-coils, and a time element that cooperates with said coil or coils to control the operation of said movable contact members in accordance with the rate at which the machines approach synchronism.

55 11. Means for connecting a dynamo-electric machine in parallel circuit with one or more other similar machines when synchronous operation is attained, comprising a main switch, means for closing the same, and a governing device for said closing means having a stationary contact member and two movable contact members, actuating-coils for said movable contact members and a variable, lost-motion connection between said movable contact members, the amount of lost motion being dependent upon the rate at which the machines approach synchronism.

60 12. The combination with an alternating-current circuit and one or more dynamo-electric machines connected thereto, of another similar machine, a switch for connecting said machines in parallel when synchronous operation is reached, a releasing and closing means for said switch comprising an electromagnet and a normally open auxiliary circuit therefor, relatively movable contact-terminals for said auxiliary circuit, actuating-coils for said terminals that are so connected to the machines as to respond to phase coincidence of the current-waves, and a governing device that operates automatically to regulate the movement of the contact-terminals in accordance with the rate of approach to synchronism.

65 13. The combination with a circuit supplied with alternating current and a dynamo-electric machine to be connected thereto, of a normally open coupling-switch, means for closing the same when released, a releasing-magnet having a normally open circuit, a generator therefor, relatively movable con-

tact-terminals for said releasing-circuit, actuating-coils for said contact-terminals that are so connected to the main alternating-current circuit and to the disconnected machine as to be responsive to phase coincidence of the two current-waves, and an automatic governor for the contact-terminals that regulates their relative movement to circuit-closing position or positions in accordance with the rate of approach of synchronism.

14. A synchronizing - governor for automatic coupling-switches, comprising a movable member having a conducting - strip, a terminal finger that normally engages said strip, a pivoted bar having a terminal finger that is normally held out of engagement with said strip, a dash-pot, one member of which is supported by said pivoted bar and the other member of which is connected to the movable member having the conducting-strip, a magnet-coil and an armature therefor that is connected to the pivoted bar.

15. A synchronizing - governor for automatic coupling-switches, comprising a switch member having a limited range of movement, a stationary terminal finger that normally engages a conducting portion of said member, a pivoted bar having a terminal finger that normally engages a non-conducting portion of said switch member, a dash-pot, one member of which is supported by said pivoted bar, a link-and-lever mechanism connecting the other member of said dash-pot with the movable switch member, a magnet-coil and an armature therefor that is connected to the pivoted bar.

16. A synchronizing - governor for automatic coupling-switches, comprising a switch member having a conducting portion and a non-conducting portion and mounted to have a limited pivotal movement, a stationary terminal finger, a pivoted bar having a terminal finger, a dash - pot, one member of which is supported by said pivoted bar, a link-and-lever mechanism connected to the other member of said dash-pot and having a lost-motion connection with said switch member, a magnet - coil and an armature therefor that is connected to said pivoted bar.

17. A synchronizing - governor for automatic coupling-switches, comprising a movable member having conducting and non-conducting contact portions, two coöperating terminal fingers, a stationary support for one of said fingers, a pivoted bar upon which the other finger is mounted, a dash-pot, one member of which is attached to said pivoted bar, a link-and-lever mechanism connected to the other member of said dash - pot, a spring and a slot-and-pin connection between said link-and-lever mechanism and the movable switch member, a magnet-coil and an armature therefor that is connected to said pivoted bar.

18. A synchronizing - governor for automatic coupling-switches, comprising a segmental insulating - block, having a surface conducting-strip, and pivotally mounted to have a limited range of movement, two co-operating contact-fingers, one of which is adjustable upon a stationary support, a pivoted bar upon which the other finger is mounted, a dash-pot, one member of which is supported by said bar, a link-and-lever mechanism connected to the other member of said dash-pot, and having a slot-and-pin and spring connection with said switch member, a magnet-coil and an armature therefor connected to said pivoted bar.

19. A synchronizing - governor for automatic coupling-switches; comprising a segmental insulating switch member having a surface contact-strip and a shoulder adjacent to one end thereof, two contact-fingers, one of which normally engages the conducting-strip adjacent to said shoulder, a pivotally-mounted bar upon which the other finger is mounted to normally engage the insulating portion of the switch member, a dash-pot, one member of which is supported by said bar, a link-and-lever mechanism connected to the other member of said dash-pot, and having a slot-and-pin and spring connection with a movable switch member, a magnet-coil and an armature therefor which is connected to said bar.

20. A synchronizing - governor for automatic coupling-switches, comprising a segmental switch member having an arc-shaped contact-surface, a portion of which is conducting and another portion of which is non-conducting, a contact-finger with which the conducting portion of the segmental switch member makes and breaks contact, a pivoted bar having a second contact-finger that also makes and breaks contact with the conducting portion of said switch member, a dash-pot, one member of which is supported by said pivoted bar, a link-and-lever mechanism interposed between the other member of the dash-pot and the segmental switch member and having a slot-and-pin and spring connection with the latter, two magnet-coils and armatures therefor that are respectively connected to the opposite ends of the pivoted bar.

21. A synchronizing - governor for automatic coupling-switches, comprising a non-conducting segment having a surface conducting-strip, a stationary conducting-finger normally in engagement with said conducting-strip, a pivoted bar, a second contact-finger supported by said bar, and normally engaging a non-conducting portion of said segment, a dash-pot, one member of which is supported by said bar, a link-and-lever mechanism interposed between the other member of said dash-pot and said segment and having

a lost-motion spring connection therewith, two solenoids and cores therefor that are respectively suspended from the ends of said pivoted bar.

- 5 22. A synchronizing-governor for automatic coupling-switches, comprising a pivoted segmental switch member having a conducting-strip and an insulating-shoulder adjacent to one end of said strip, a stationary contact-finger normally engaging said conducting-strip adjacent to said shoulder, a pivoted bar, a contact-finger supported by said bar and normally engaging the insulating-surface of the segmental switch member 10 adjacent to the other end of the conducting-strip, a dash-pot, one member of which is suspended from one end of the pivoted bar, a link-and-lever mechanism interposed between the other member of said dash-pot and the segmental switch member, and having a lost-motion spring connection therewith, a spring tending to separate the dash-pot members, a solenoid and a core therefor which is attached to the end of the pivoted lever 15 20 25
25. A synchronizing-governor for automatic coupling-switches, comprising a pivoted segmental switch member having an arc-shaped surface, a portion only of which is formed of conducting material, an adjustable, stationary contact-finger that normally engages the conducting portions of the pivoted switch member, a pivoted bar having a contact-finger that normally engages the non-conducting surface of the pivoted switch member, a dash-pot, one member of which is supported by one end of said bar, a link-and-lever mechanism connected to the other member of said dash-pot, and having a lost-motion spring connection to the pivoted switch member, a spring tending to normally separate the dash-pot members, a solenoid and a core therefor, that is suspended 30 35 40 45 from the end of the pivoted bar which is op-

posite that to which the contact-finger and the dash-pot member are attached.

24. A synchronizing-governor for automatic coupling-switches, comprising a pivotally-mounted switch member having an arc-shaped contact-surface, a portion only of which is conducting and having an insulating-shoulder adjacent to one end of the conducting portion, a stationary contact-finger normally engaging the conducting portion of the switch member but adapted to engage the insulating-shoulder when the switch member is moved in one direction, a pivoted bar, a second contact-finger mounted upon said bar and normally engaging the non-conducting portion of the pivoted switch member, a dash-pot, one member of which is attached to said member, a link-and-lever mechanism connected to the other member of said dash-pot, and having a lost-motion spring connection to said pivoted switch member, means tending to separate the dash-pot members, a solenoid and a core therefor that is attached to said pivoted bar.

25. The combination with a main switch, and a normally open governing-circuit therefor, of means for controlling the action of said governing-circuit, comprising a segmental switch member that is mounted to have a limited degree of rotative movement, two operating contact-fingers, one of which is stationary and the other movable, one or more magnet-coils arranged to actuate the movable contact-finger and a dash-pot mechanism that is interposed between said finger and said segmental switch member and has a limited lost-motion connection with the latter.

In testimony whereof I have hereunto subscribed my name this 7th day of April, 1905. 85

HUGH J. McMAHAN.
